UNITED STATES PATENT OFFICE.

LEROY D. GILLETTE, OF WOODHULL, ILLINOIS.

MULTIPLE-REEL ATTACHMENT FOR MOVING-PICTURE MACHINES.

1,291,829.

Specification of Letters Patent.

Patented Jan. 21, 1919.

Application filed March 29, 1917. Serial No. 158,291.

To all whom it may concern:

Be it known that I, LEROY D. GILLETTE, a citizen of the United States, and a resident of Woodhull, in the county of Henry and State of Illinois, have invented a certain new and useful Multiple-Reel Attachment for Moving-Picture Machines, of which the following is a specification.

My invention relates to an attachment to moving-picture machines by the use of which several films (which come to the producer, as a rule, in 1000 feet lengths,) may be wound upon a single reel and run thence continuously through the projector.

One of the objects of the invention is to run continuously a film consisting of several reels, whereby the delay caused by changing reels is obviated.

Another object is to provide means by the use of which the producer may give, with a single machine, an exhibit without interruptions—a result attained heretofore only by the use of two sets of machines.

A still further object is to save the operator a large amount of hurried work, either in changing reels or in changing machines.

A further object is to transform a hand-driven machine into a motor-driven one.

It is an object to so arrange the elements constituting my improvements that the several films will pass to and run through the projector in proper order—i. e., initial ends first.

Another object is to provide means whereby the continuous or united film may be run backward and the individual parts thereof severally wound upon individual reels adapted and purposed therefor.

Many minor objects will presently appear. Some of these will be obvious and others particularly pointed out.

The invention consists, substantially, in improvements of the nature hereinafter disclosed.

In the accompanying drawings, which illustrate a favored embodiment of my invention:

Figure 1 is a side elevation;

Fig. 2, a front elevation;

Fig. 3, an enlarged sectional detail presently more fully described; and

Fig. 4, a top-plan detail.

Coming now to a detailed description of the drawings, 2 indicates a supporting frame comprising front legs 3, 3', rear legs 4, 4', and connecting strips 5 and 6.

7 designates the usual lamp-house and 8 the projector, mounted on a table 9 fulcrumed approximately at its midlength, by means of rod 10, between the legs 4, 4'. 60 11, 11 indicate a pair of legs secured one to each corner of the table. Each leg 11 comprises an upper section 11' having a series of apertures 11'', and a lower section 11' having a series of apertures 11''. Each pair 65 of coacting sections is adjustably united by means of a bolt 12 and nut 12' in an evident manner, whereby the table may be tilted on said fulcrum to direct the lenses properly toward the screen. 70

15 designates one of the reels on which the films are received from the supply concern. It is fixed on a shaft 16 on which is also fixed a pulley 17. The axle 16 may be slipped into oppositely arranged bearings in 75 the legs 3, 3' by means of slots 18 cut therein.

19, 19' designate a pair of side-bars connected at their respective ends each to a front and a rear leg. 20 indicates a motor mounted on a block 21 secured on the rear 80 ends of said bars. 22, 22 indicate a pair of oppositely arranged bearings, one on each bar 19, 19'. 23 denotes a counter-shaft mounted in said bearings. A sheave 24 is fixed on the shaft 23 adjacent the leg 3'. 85 An expansion spring 24 embraces said shaft, one of its ends bearing against a fixed collar 25 and the other against a loosely mounted annulus 26 both of which are also on said shaft. 27 designates a slip-disk or pulley 90 loosely mounted on said shaft. 28 indicates a clutch-block having a plurality of grooved-sections 28^a, 28^b, 28^c, gradually increasing in diameter. Its inner face is recessed to provide shoulders 29 adapted to engage a pin 30 fixed in the shaft 23, and its outer end is recessed to provide shoulders 31 adapted to be engaged by the teeth of a slotted clutch-member 32 slidable by means of a pin 33 on said shaft. 34 designates a collar 100 and 35 a pin extending transversely through the shaft. The clutch-member 32 may be thrown into or out of engagement with the coacting member 28 by means of a rod 36 having a knob 37. The shaft 23 is driven by 105 a belt 38 which embraces a balance-wheel 39 mounted on said shaft, and also the drive-pulley 20' on the motor 20.

Seated in bearings provided by cutting arcuate slots 44 in the rear legs 4, 4' is a 110 shaft 40 on which is fixed a reel or magazine 41 having a projecting hub 42 traversed

and driven by a spring-belt 43 which, because of its elasticity, may be made to engage either of the pulley-sections 28^a, 28^b, or 28^c, by which it is driven. The pulley 17 is 5 driven by a belt 46 actuated by a sheave 47 fixed on the shaft 23.

A belt 48 embraces the sheave-block 28 and the sheave 49 on the projector.

A double sheave 50 and an idler 51 are 10 mounted on a shaft 51' seated in bearings in the legs 3, 3'. 52 denotes a belt deriving motion from the sheave 24 and driving the sheave 50. Mounted in bearings 53 in the legs 4, 4' is a removable shaft 54 on which 15 are fixed a sheave 55 and a film-display reel 56. A belt 57 driven by one side of the double sheave 50 embraces the sheave 55 to thus drive the reel 56.

58 indicates the film, comprising a plurality of parts, each usually 1000 feet in 20 length, the initial end of each of which is cemented or otherwise secured to the terminal end of the preceding one.

For the purposes of this specification the 25 reel 15 may be termed a shipping-reel, inasmuch as it is one of those on which the individual films or film-sections are shipped; the reel 41 may be termed the reversing-reel, for the films are reeled upon it in reverse 30 order from those on the several shipping reels; and the reel 56 may be designated the feed-reel, inasmuch as the united film-sections are fed therefrom to the projector.

In operation, the axle of the primary 35 shipping-reel, on which is wound the film illustrating first part of the picture, is passed through the slots 18 in the legs 3, 3' and seated on its bearings. Its initial end is then removably engaged with the hub 42 40 of the reversing reel in any suitable manner. Upon the motor 20 being started, the film will be run onto the reel 41. This movement and some of the succeeding ones are, in order to avoid confusion, not illustrated.

45 The film is shown as in the process of being exhibited, and the several arrows indicate the directions of the movements of the adjacent elements. When its terminal has been reached, a reel 15 containing the second 50 part of the picture is substituted for the one just emptied, and the terminal end of the first strip of film cemented to the initial end of the second sheet. This procedure is followed until all the individual film-strips 55 are united into a continuous film upon the reel 41. Thereupon the terminal of the last film-sheet is to be secured to the hub of the feed-reel 56, the motor, (which was stopped 60 during each of the operations just described,) again started, and the continuous film will be wound upon the reel 56, its initial end being the last to be wound and therefore accessible. When the exhibit is 65 to be started the film is to be passed through the projector 8 in the usual manner, its

initial end thus passing first, and said end is then secured to the usual clasp (not shown) on the reel 41. When the picture has been displayed the entire film will have been rewound upon the reel 41 and its terminal accessible for securement to the hub 55, ready for another exhibition.

Owing to the fact that each outer coil of the film contains many times the number of inches contained in an inner coil, each revolution of the reel 56 would at first, unless some provision thereagainst was made, run too rapidly through the projector—much more rapidly of course than it would run when unwinding from the inner coils; therefore I provide the slip-disk 26, which may be governed by adjustments of the spring 25 to cause the disk to run fast, slow, or at any intermediate speed desired.

When the show has closed the accessible 85 terminal of the film is secured to the fastener (not shown) common to all shipping reels, and that film-section which was last attached to a preceding one, wound on one of the reels 15. The cement fastening is then 90 dissolved and the reel and its contained film removed. Each succeeding film-section is to be likewise separated from the preceding one, and each wound upon one of the shipping reels. It is to be noted that the terminal 95 or last end of each of the sections is the one to be secured to the shipping reel, and that therefore its initial end will be the last to be wound and therefore accessible and in proper order to be run through machines of 100 either this or preceding types. When the film is being wound onto the several shipping-reels the belts 52 and 57 may be disengaged from the pulleys. The belt 46 may be disengaged during the time the picture is 105 being exhibited.

If in reeling the film either onto or off from the reel 56 there is unusual strain placed upon the film it would, unless provision thereagainst was made, be torn or 110 broken. In order to prevent this I provide the slip-pulley 27 which is held lightly in contact with the faces of the blocks 26 and 28 by means of the spring 25.

The clutch-member 32 is thrown into or 115 out of engagement with the member 28 by means of the rod 36, button 37 and link 37'.

I realize that considerable variation is possible in the details of this construction without departing materially from the spirit 120 of my invention. Therefore I do not intend to limit myself to the specific structure or arrangement herein shown and described except as pointed out in the following claims, wherein it is my intention to claim as 125 broadly as is permitted by the state of the art all the novelty inherent in the invention.

I therefore claim as new:

1. The combination in a moving-picture machine, with a sectional film, of a ship- 130

ping-reel on which a section of the film is wound, a reversing-reel on which the film is wound from the shipping-reel, and a feed-reel upon which the film is wound from the reversing-reel.

2. The combination in a moving-picture machine, with a sectional film, of a plurality of shipping reels on each of which one of the film sections may be wound, a holder 10 wherein said reels may be successively placed, a reversing-reel on which the films are wound from the shipping reels, and a feed-reel upon which the films are wound from the reversing reel.
- 15 3. The combination in a moving-picture machine, of a shipping-reel and a film wound thereon, means for unwinding it and thus reversing the order in which the film was wound upon the shipping-reel, and means 20 from which the film passes in its proper order to the projector.

4. The combination in a moving-picture machine, of a shipping-reel and a film wound thereon, means for unwinding the 25 film therefrom and simultaneously rewinding it in the reverse order from that in which it was wound upon said reel, and means from which the film passes in its proper order to the projector.

30 5. The combination in a moving-picture machine, of a shipping-reel and a film wound thereon, a reel onto which the film may be wound in a reverse order, and means whereby it passes through the projector in 35 an order contrary to that last recited.

6. The combination in a moving-picture machine, of a shipping-reel and a film wound thereon, a reel onto which the film may be wound in a reverse order from that 40 in which it was wound on the shipping reel, a feed-reel onto which the film may be thence wound in the same order in which it was wound upon the shipping reel, and means for simultaneously rotating the ship- 45 ping-reel and the second recited reel.

7. The combination in a moving-picture machine, of a shipping-reel and a film wound thereon, a reel onto which the film may be wound in a reverse order from that 50 in which it was wound on the shipping reel, a feed-reel onto which the film may be thence wound in the same order in which it was wound upon the shipping reel, and means for simultaneously rotating the two 55 last recited reels.

8. In a moving-picture machine, and in combination a film, a reel from which the

film is fed through the projector, a reel onto which it is wound, after passing through the projector, in reverse order from that in 60 which it was wound on the first recited reel, and a shipping-reel onto which the film is wound in the same order in which it was wound upon the first recited reel.

9. In a moving-picture machine, and in 65 combination a film, a reel from which the film is fed through the projector, a reel onto which it is wound, after passing through the projector, in reverse order from that in which it was wound on the first recited 70 reel, a shipping-reel onto which the film is wound in the same order in which it was wound upon the first recited reel, and plural means for actuating said reels.

10. In a moving-picture machine, the 75 combination, of a shipping-reel, clutch-mechanism from whence it derives rotary movement, a film wound on said reel, means for changing the order of motion of the film, and means for again changing the 80 order of movement of the film, the film passing from the last recited element to the projector, and means for throwing the clutch-mechanism into or out of operative position.

11. In a moving-picture machine having 85 a frame adapted to support successively placed shipping-reels, each of which carries one unit of a sectional film, the combination with said reels and film units of a reversing- 90 reel adapted to successively receive the film units after they have passed in predetermined order from the successively placed shipping-reels and after their adjacent ends have been united, and a feed-reel onto which 95 the united film-units are wound after passing from the reversing-reel.

12. In a moving-picture machine having 100 a frame adapted to support successively placed shipping-reels, each of which carries one unit of a sectional film, the combination with said reels and film units of a reversing-reel adapted to successively receive the film units after they have passed in predetermined order from the successively placed 105 shipping-reels and after their adjacent ends have been united, a feed-reel onto which the united film-units are wound after passing from the reversing-reel, and a projector through which the united film-units pass 110 from the feed-reel in exhibiting order.

In witness whereof I hereto subscribe my name this 14th day of March, 1917.

LEROY D. GILLETTE.
